SOLVENT REFINING OF MINERAL OIL

Daniel Stryker, White Plains, and James H. Grahame, Mount Vernon, N. Y., assignors to The Texas Company, New York, N. Y., a corporation of Delaware

Application May 10, 1934, Serial No. 724,852

1 Claim. (Cl. 196—18)

This invention relates to the process of refining mineral oil with solvents for the production of lubricating oils.

The invention contemplates the manufacture 5 of lubricating oil from mixed-base crudes and the like containing asphaltic, naphthenic and paraffinic constituents, including wax, wherein the oil is treated with a solvent adapted to precipitate the asphaltic constituents, then extracted with an 10 extraction solvent adapted to separate and remove the naphthenic constituents of low lubricating value, and thereafter the extracted oil is dewaxed.

The invention contemplates effecting the removal of the asphaltic, naphthenic and wax constituents through the agency of a common solvent. 15 A solvent suitable for this purpose is one which is adapted to precipitate the asphaltic constituents while retaining the remaining oil in solution, 20 and which is also adapted to serve as a diluent during the subsequent extraction and dewaxing steps. Such a solvent may comprise, for example, a light petroleum fraction of the character of propane, or which may comprise a mixture of 25 light hydrocarbons, such as ethane, propane and butane.

The invention, therefore, comprises mixing a wax-bearing lubricating oil fraction of crude oil with a light petroleum fraction of the character 30 of propane, in sufficient proportion to precipitate the asphaltic constituents of the oil, while retaining the wax and remaining oil in solution. The precipitated asphaltic constituents are then removed from the dilute mixture, following which 35 the dilute mixture is subjected to extraction with an extraction solvent having a selective action as between naphthenic and paraffinic constituents of the oil of the character of furfural, acetone, nitrobenzene, etc.

The presence of the diluent in the oil undergoing extraction serves to bring about a more effective and intimate contact between the extraction solvent and the oil. It also facilitates the resulting separation of the oil and solvent 45 into naphthenic and paraffinic layers. These resulting layers are separately removed from the extracting zone and the paraffinic or raffinate layer may then be dewaxed. Dewaxing of this raffinate fraction may be readily effected, since 50 it is already in a dilute condition. Furthermore, it also contains a proportion of the extraction solvent which acts as an anti-solvent for the wax. If desired, additional quantities of diluent and anti-solvent may be added thereto to further 55 facilitate the removal of wax. The quantities of

diluent and wax anti-solvent liquid thus added are sufficient to form a solvent liquid mixture having selective action as between oil and wax at temperatures of the order of 0° F.

The actual removal of the wax may be effected 5 by any of the well known methods, including centrifuging, settling or filtering, and where filtration is used the wax may be filtered from the mixture in the presence of a suitable filter-aid material.

An important advantage of our invention 10 resides in effecting removal of the asphaltic and naphthenic bodies prior to dewaxing. This is particularly true where the dewaxing is carried out by filtration methods.

There are certain constituents of the oil removed along with the asphaltic and naphthenic bodies, which apparently inhibit the separation of the wax in a readily filterable form, and which also impede subsequent filtration. These constituents are of such a nature that they may not be sufficiently removed by extraction alone, or by the deasphalting step alone. It has been found advantageous, therefore, to subject the oil to a deasphalting as well as a solvent extraction 25 treatment prior to dewaxing.

In order to more clearly describe the invention, reference will now be made to the accompanying drawing forming a part of the specification.

The oil to be refined, for example, a viscous wax-bearing residual lubricating oil fraction, such as derived from Mid-Continent crude, is conducted from a tank 1 through a pipe 2 to a mixer 3. Liquid propane is conducted from a tank 4, through 35 a pipe 5, to the mixer 3. The proportions used may comprise three or four volumes of propane to about one volume of oil, although a larger proportion of propane may be required, depending upon the characteristics of the oil undergoing treatment.

The mixing is advantageously effected at around 90° or 100° F., following which the mixture is introduced to a settling chamber 6 wherein the asphaltic constituents insoluble in the propane precipitate from the mixture and are removed through an outlet 7.

After removal of the asphaltic material, it may be desirable, in some instances, to either remove part of the propane diluent, or to add a further 50 quantity, depending upon the character of the stock being treated.

The remaining portion of wax-bearing oil and propane is then conducted from the settler 6 through a pipe 8 to an extracting chamber 9. 55

This extracting chamber is advantageously of the countercurrent tower type wherein the dilute oil is introduced to the lower portion of the chamber and caused to rise upwardly therethrough. The extraction solvent is introduced to the upper portion of this chamber and descends downwardly therethrough in direct contact with the upwardly moving body of dilute oil. The chamber may or may not be provided with contacting means, such as baffles or other packing material, as desired.

The extraction solvent, which in this instance comprises furfural, is conducted from a tank 10 through a pipe 11 to the upper portion of the chamber 9, and may be introduced thereto at a temperature of around 100° F., or at higher temperatures of around 200° to 300° F.

The temperature of the furfural entering the chamber may be regulated by its passage through 20 a suitable heat exchanger 11a.

The proportion of furfural to oil mixture may comprise about two parts of furfural to one part of mixture. Either smaller or larger proportions of furfural to oil may be used, depending upon 25 the degree of extraction desired, as well as upon the nature of the oil undergoing treatment.

Due to the selective action of the furfural upon the oil, the mixture separates into fractions respectively rich in naphthenic and paraffinic constituents. The naphthenic constituents, dissolved in furfural, are removed as extract from 30 the bottom of the chamber 9 through an outlet 12.

The paraffinic constituents, including wax 35 mixed with a large amount of propane and some furfural, are removed as raffinate from the top of the chamber 9 through a pipe 13.

The raffinate is then conducted through a mixer 14 and a chilling coil 15, wherein the mixture 40 is chilled to temperatures of the order of 0° F. and below in order to solidify the wax. It may be desirable, prior to chilling, to increase the amount of diluent present, in which case additional quantities of propane are conducted from 45 the tank 4 through a pipe 16 to the inlet of the mixer 14, wherein it is mixed with the raffinate.

Likewise, additional quantities of furfural may be added to the raffinate by line 17 prior to its introduction to the mixer for the purpose of rendering the solvent mixture less soluble towards 50 the wax.

Instead of using furfural as the anti-solvent, it is contemplated that other selective solvent liquids, such as acetone and methyl ethyl ketone, 55 may be used.

In some cases, it may be unnecessary to add additional anti-solvent liquid since the raffinate, as it leaves the extraction chamber 9, may contain sufficient furfural to serve as a wax anti-solvent.

60 The chilled wax-bearing mixture is then conducted through a pipe 18 to a filter 19 wherein the wax is separated in the form of a filter cake. The resulting filtrate is removed from the filter and collected in a tank 20, while the filter cake 65 is accumulated in the tank 21.

If it is desired to use a filter-aid material, the chilled mixture may be conducted from the chilling coil 15 directly to a mixer 22, wherein it is mixed with filter-aid material, such as fuller's earth, diatomaceous earth, and the like, from a storage bin 23. The resulting mixture, containing suspended wax and filter-aid material, is then conducted to the filter 19 wherein the wax is separated in the presence of the filter-aid material.

10 The solvents contained in the filtrate and wax may be removed by distillation or in any other suitable manner, and recovered for re-use.

The invention is not restricted to the particular operating conditions described in the foregoing example. The temperatures therein set forth may be varied, depending upon the nature of the oil undergoing treatment. It is contemplated that a closed system will be used capable of withstanding pressures sufficient to maintain 20 the propane or other normally gaseous diluent petroleum fraction in a liquid state.

The invention is not limited to the treatment of residual lubricating oil fractions, as above described, but is also adapted to the treatment of 25 distillate lubricating fractions. It is also contemplated that the process may be applied to viscous wax-bearing cylinder stocks.

Obviously, many modifications and variations 30 of the invention, as hereinbefore set forth, may be made without departing from the spirit and scope thereof, and therefore only such limitations should be imposed as are indicated in the appended claim.

We claim:

In the process of manufacturing lubricating oil from residual lubricating oil stock containing large amounts of wax, such as derived from Mid-Continent crude, the method comprising diluting the wax-bearing oil with propane in sufficient quantity to precipitate the asphaltic constituents while retaining the remaining oil and wax in solution, removing the asphaltic constituents so precipitated, extracting the remaining solution of wax-bearing oil in propane with furfural at a 45 temperature in the range of 200° to 300° F. whereby the mixture is separated into a raffinate phase comprising wax and liquid paraffinic constituents of the oil, propane and a substantial amount of furfural, and an extract phase comprising naphthenic constituents dissolved in furfural, removing the extract phase, adding a further quantity of a non-hydrocarbon solvent having anti-solvent action for wax, to said raffinate phase to form with the retained furfural and propane a solvent 50 mixture exerting selective action as between wax and oil at a temperature of around 0° F., chilling the resultant mixture to precipitate solid hydrocarbons, removing the solid hydrocarbons so precipitated in the presence of the entire amount 60 of anti-solvent liquid, including that initially contained in the raffinate phase, and recovering the solvent from the resulting dewaxed oil.

DANIEL STRYKER.
